UNITED STATES PATENT OFFICE.

LOUIS GLEMBY, OF NEW YORK, N. Y.

HAIR NET.

Application filed June 8, 1923. Serial No. 644,086.

In the manufacture of hair nets of the type known as cap-shape, it has heretofore always been the custom to produce the cap-shape of the net by forming a number of 5 rows of meshes at the outer or lower edge of the net (usually two rows) of smaller dimensions than the rest of the net, all the remaining meshes next to the outer or lower two rows being of the same dimensions. The 10 narrowed lower end of the cap-shape is produced by these two lower rows of smaller sized meshes because of the fact that there are an equal number of meshes in each row, consequently as the meshes of the lower rows 15 are smaller than the remaining rows, the dimensions of the net at the lower edge are smaller than the dimensions of the main portions of the net, thus providing a restricted opening in which the hands are 20 placed to stretch this restricted opening, as the net is being drawn over the hair.

These lower rows of meshes spring back, after the net has been placed over the hair and the hands have been withdrawn, and 25 form, in effect, a clamping band which acts to keep the net securely in place. As hair nets are constructed of very fine strands, commonly of human hair, they are very fragile, and as the clamping effect of the cap 30 shape nets has heretofore only been produced by the two lower rows of small meshes, the strands forming these lower meshes are not only frequently broken when the net is stretched to place the same over the hair, 35 but also as there are only two rows of these smaller outer or lower meshes, the resiliency necessary to produce the required clamping effect is not sufficient to cause the return of the restricted opening to its original size, 40 particularly after the net has been fully stretched. The result of this failure of the opening to return to its original dimensions is to destroy the desired clamping effect and therefore not only prevents the net from 45 staying securely in position, but also an objectionable bagging of the net is produced around the edges of the hair which detracts greatly from the neat appearance which it is the primary purpose of the net to attain. 50 The object of the present invention therefore is to provide a new and improved construction of a cap-shape hair net which will overcome the objections hereinbefore set forth.

For the accomplishment of this object and such further objects as will be apparent to those skilled in the art to which this appertains, the invention consists in the construction of the hair net and the arrangement and combination of the meshes thereof, hereinafter specifically described in the following specification, wherein is shown a preferred embodiment of my invention, but it is to be understood that such changes, modifications and variations may be resorted to 65 which fall within the scope of the claims hereunto appended.

In the drawings forming a part hereof, Fig. 1 is a side view on a reduced scale, 70 of a hair net embodying my invention. Fig. 2 is an enlarged partial view of the lower part of the hair net shown in Fig. 1 in its normal or contracted position, and Fig. 3 is a view similar to Fig. 2 showing the net in its stretched condition. 75

As shown in the drawings, the net 10 is formed into what is known in the art, as a cap-shape having a restricted opening 11 at the lower edge thereof. The main body portion of the net is formed of a plurality 80 of rows 12 of relatively large meshes, all of which are of the same dimensions. The strands forming the meshes of the net extend vertically across the net (as seen in Fig. 1) from one side of the opening 11 to the other side thereof. A plurality of rows 13 preferably three rows of smaller meshes are formed, which rows extend around adjacent the opening 11. The strands are then tied to form a number of rows 14 of meshes, 85 intermediate in size between the small meshes of the rows 13 and the large meshes of the rows 12. Four rows of these intermediate sized meshes are preferably provided. It will be noted by referring to Figs. 1 and 2, 90 that while the sides 13^a of the substantially rectangular meshes of each of the intermediate rows of equal length, that the rectangular meshes of the top intermediate row are 95 longer than the middle intermediate rows because of the fact that these top meshes are formed by two lower sides 14^a and two upper sides 12^a. The rectangular meshes of the lowermost row of intermediate meshes are formed by two upper sides 14^a and the two lower sides 13^a. It will also be noted 100 that because of the converging direction of the vertically extending strands of the net 105

towards the restricted opening, that the horizontal diagonal dimensions of the meshes of the intermediate rows 14 increase progressively from the lowermost to the uppermost rows of these meshes.

The result of these progressive differences in these horizontal diagonals is to cause the meshes of each of the intermediate rows 14 to exert a tendency to spring back to their normal positions, shown in Fig. 2, when the net is stretched to the position shown in Fig. 3, so that each of the intermediate rows will exert a resilient effect which increases gradually in each row from the uppermost to the lowermost intermediate rows. Therefore the resilient properties of a net constructed in accordance with the principles herein disclosed are greatly increased over the old constructions, as the tendency of the lowest rows 13 to return to their normal positions is augmented by the resilient effect of the intermediate rows. Because of the differences of the distortions produced in each row of the intermediate meshes the strains produced by distorting the net are substantially distributed over a large number of rows, thereby not only assisting to prevent breakage of the strands but also increasing very greatly the resiliency of the nets. Furthermore the clamping effect of the net when in use is distributed over a larger or wider band thus adding to the comfort of the wearer.

Having thus described my invention, what I claim as new and desire to secure by Letters Patent of the United States is:

1. A cap shape hair net having a main body portion comprised of strands interengaged to form a plurality of rows of relatively large sized meshes, a plurality of rows of relatively small meshes adjacent the lower edge of said net to form a restricted opening and a plurality of rows of intermediate sized meshes interposed between and connecting the rows of said large and small meshes, said rows of intermediate sized meshes cooperating with the rows of smaller meshes to resiliently resist deformation of said restricted opening.

2. A cap shaped hair net comprised of a plurality of strands interwoven to form series of rows of large, small and intermediate sized meshes, said rows of large sized meshes forming the upper major portion of the net, said small meshes forming the lower portion of the net and defining a restricted opening and said intermediate sized meshes being interposed between said large and small meshes.

3. A cap shape hair net comprised of a plurality of strands arranged to form a lower open meshed portion terminating at its lower edge in an opening, and an upper or top open meshed portion of relatively greater dimensions than said lower portion,

and said strands being interengaged to form a plurality of meshes increasing in size from said opening to said top portion.

4. A cap shape hair net comprising a plurality of strands arranged to form a lower open meshed portion terminating at its lower edge in an opening, and an upper or top open meshed portion of relatively greater dimensions than said lower portion, and said strands being interengaged to form a plurality of substantially rectangular meshes, the linear dimensions of the sides of said rectangular meshes increasing in size from said bottom portion of said net to said top portion.

5. A cap shape hair net comprised of a plurality of strands arranged to form a lower open meshed portion terminating at its lower edge in an opening, and an upper or top open meshed portion of relatively greater dimensions than said lower portion, and said strands being interengaged to form a plurality of substantially horizontally extending rows of meshes, the meshes forming each horizontal row being of equal dimensions, the meshes of the bottom rows of the net adjacent said opening being of smaller size than the meshes of the rows of said upper portion of the net, and a plurality of rows of intermediate sized meshes located between the rows of said bottom and upper portions.

6. A cap-shaped hair net comprised of a plurality of strands arranged to form a lower open meshed portion terminating at its lower edge in an opening, and an upper or top open meshed portion of relatively greater dimensions than said lower portion, each of said strands extending in substantially vertical directions from one side of said opening across said top portion to a substantially diametrically opposite point of said opening and being interengaged to form a plurality of horizontally extending rows of meshes, the meshes forming each horizontal row being of equal size, the meshes of the bottom horizontal rows adjacent said opening being of small size, the meshes of the horizontal rows of the upper or top portion being of relatively larger dimensions and a plurality of rows of meshes intermediate in size between the smaller and larger sized meshes connecting and interposed between the upper and lower rows.

7. A cap shaped hair net comprised of a plurality of strands arranged to form a lower open meshed portion terminating at its lower edge in an opening, and an upper or top open meshed portion of relatively greater dimensions than said lower portion, and said strands being interengaged to form a plurality of series of rows of large, small and intermediate sized meshes, the series of rows of smaller meshes being adjacent said opening, the series of rows of larger meshes

5 forming the top portion of said net, the series of rows of intermediate meshes merging into and interposed between and connecting the rows of smaller and larger meshes, and the meshes of the rows of each respective series being of equal dimensions.

- 10 8. A cap shape hair net comprised of a plurality of strands arranged to form a lower open meshed portion terminating at its lower edge in an opening, and an upper or top open meshed portion of relatively greater dimensions than said lower portion, said strands being interengaged to form a plurality of series of horizontally extending rows of large, small and intermediate sized substantially rectangular meshes, the sides of the rectangular meshes of the horizontally 25 extending rows of each of the respective series being substantially equal, and the horizontal diagonal dimensions of the rectangular meshes of each horizontal row increasing gradually from the bottom towards the 30 top of the net.
- 15 9. A cap shape hair net comprised of a plurality of strands arranged to form a lower open meshed portion terminating at

its lower edge in an opening and an upper or top open meshed portion of relatively greater dimensions than said lower portion, said strands being interengaged to form a plurality of series of horizontally extending rows of large, small and intermediate sized substantially rectangular meshes, the sides of the rectangular meshes of the horizontally 35 extending rows of each of the respective series being substantially equal, and the horizontal diagonal dimensions of the rectangular meshes of each horizontal row increasing gradually from the bottom towards the 35 top of the net.

10 10. A hair net of interwoven strands, having a central portion of relatively large mesh, and a plurality of rows of mesh, gradually decreasing in size, surrounding the 40 said central portion.

In testimony whereof I have affixed my signature.

LOUIS GLEMBY.
